United States Patent Office.

JOHN G. BOYD, OF DECATUR, TEXAS, ASSIGNOR TO HIMSELF AND ALLEN BAILEY, OF SAME PLACE.

Letters Patent No. 101,574, dated April 5, 1870.

IMPROVEMENT IN SULKY PLOWS.

The Schedule referred to in these Letters Patent and making part of the same.

To all whom it may concern:

Be it known that I, JOHN G. BOYD, of Decatur, in the county of Wise and State of Texas, have invented certain new and useful Improvements in Sulky Plows; and I do hereby declare that the following is a full and exact description thereof, reference being had to the accompanying drawings making a part of this application.

The object of my invention is to provide an economical and certain means for regulating the depth of furrow, and consists in hanging the beam as will be hereinafter more fully set forth.

To enable those skilled to make and use my improved sulky plow, I will proceed to describe the construction and operation of the same, referring by letters to the accompanying drawings.

Figure 1 is a top view;

Figure 2, a side view; and

Figure 3, a front view on a reduced scale.

Similar letters of reference denote like parts in the several views.

A A are the two wheels, and

B, the axle of the sulky, the former secured in the usual manner by pins a.

At equal distances from the wheels are erected, upon the axle, two uprights C C, to which is secured the driver's seat D, the standards shouldered at the upper side of the axle, and their lower ends protruding a short distance below the axle, to serve as guides for the beam, as will be presently explained.

E is the beam, provided, near to either end, with tongues F F', the front end being also furnished with a clevis, G, and staples b.

The tongues are provided with any desired number of holes, for the purpose presently explained, the standards C C being furnished in a like manner with holes for the reception of a pin, d.

The axle, on its under side, is recessed or cut away to form a seat for the beam E, which is secured to the sulky and held in place by means of a lever-bar, H, passing between the two uprights, to which it is secured by the pin d. The tongues F F' of the beam passing up through slots formed at either end of the lever-bar, are secured to the same by pins or bolts.

The plow-shares are secured to the beam by means

of the screw-bolts e, and adjustable braces I I, provided with adjusting-nuts f f'.

Brace rods J J, running from the staples b b to similar staples g g on the axle, prevent any forward movement of the beam, which is raised and lowered in parallel lines in the following manner, to wit:

The pin K, being withdrawn from the tongue F, the rear end of the lever-bar is elevated, which lifts the sulky in a perfectly vertical line a distance equal to the distance traveled by the lever, or, in other words, drives the plow-points into the ground. The pin K is then put through the hole in the tongue F immediately under the lever, which holds it in place, and, consequently, the furrow made will be of uniform depth.

The protruding portions of the uprights serve as guides to the beam and prevent any lateral movement.

The object of the series of holes in the uprights and the tongue F' will readily be understood to be for the purpose of regulating the extent of the movement of the beam by the lever-bar.

It will thus be seen that the depth of furrow having been determined upon, the beam is set accordingly, and the driver takes his seat and is relieved of all the skill and labor necessary in making a furrow of uniform depth.

I have discovered, by practice, that square corners are easily turned with my improved plow, and all work required to be done by it readily and easily accomplished. Of course the number of furrows may be increased by slight modifications in the design, without departing from the spirit of my invention.

Having thus described the construction and operation of my improved plow,

What I claim as new, and desire to secure by Letters Patent, is—

The lever H, fulcrumed at d, the standards F and F', beam E, and guides C, all arranged and operating substantially as and for the purposes set forth.

In testimony whereof I have hereunto set my hand and seal this 4th day of November, 1869.
